CONTROL AND OPERATING MECHANISM
FOR UNLOADING WASHERS

Frank A. Gerlach, Cincinnati, Ohio, assignor to
The American Laundry Machinery Company,
Norwood, Ohio, a corporation of Ohio

Application September 14, 1936, Serial No. 100,594

11 Claims. (Cl. 68—210)

This invention relates to improvements in washing machines and more particularly to improvements in operating and control mechanism for a washing machine of the self-unloading type.

One of the objects of the present invention is to provide in a self-unloading washing machine means for lifting the washing cylinder out of its casing for an unloading or dumping operation, and a train of mechanical connections for rotating the cylinder during a washing operation which remains in driving relation throughout the unloading or dumping operation. One of the disadvantages of prior constructions was that the driving connections for rotating the cylinder were broken during a dumping operation and difficulties were involved in re-establishing the driving connection after the dumping operation.

The present invention provides a single motor drive for all of the operations of the machine with novel disconnectible driving connections for producing the various operations as desired.

Among the novel features of the present invention are operating circuits for the motor drive and a novel control means so arranged that the circuits for one machine operation are automatically broken when the circuits for another machine operation are established. The control means is so arranged that the proper driving connections are established coincidentally with the movement of the control means to establish the proper motor energizing circuits for the desired operation.

The present invention provides novel control means whereby a reversible motor is utilized for rotating the washing cylinder in opposite directions for a washing operation and the reversible features of the motor are also utilized in spotting the cylinder in proper position for access to the interior of the washing machine or for a dumping operation and the reversing motor is also used to control the lifting of the cylinder bodily out of and into the surrounding casing.

Other novel features will be found in various details of the operating and control mechanism which will be pointed out in connection with the description of the embodiment disclosed in the drawings and the essential features will be summarized in the claims.

In the drawings, Fig. 1 is a front elevation of a washing machine embodying my invention, a portion of the right and left hand end coverings being broken away to expose the drive mechanism;

Fig. 2 is an enlarged end elevation of the right hand end of the machine shown in Fig. 1, the

cover being removed and parts of the frame broken away to more clearly show the construction;

Fig. 3 is a plan view of the right hand end of the machine with the cover removed; 5

Fig. 4 is a partial sectional view taken along the line 4—4 of Fig. 1;

Fig. 5 is an enlarged partial sectional plan view through the driving mechanism taken along the line 5—5 of Fig. 2; 10

Fig. 6 is a sectional view along the line 6—6 of Fig. 1;

Fig. 7 is a sectional view taken along the line 7—7 of Fig. 6;

Fig. 8 is a fragmental sectional elevation of a 15
detent device and switch in the cylinder rotating position, showing their association with the operating lever, the view being taken along the line 8—8 of Figs. 2 and 3 with the lever shown in a plane 90° from the rest of the mechanism; 20

Fig. 9 is a view similar to Fig. 6 showing the cylinder lifted out of the casing for a dumping operation;

Fig. 10 is a view similar to Fig. 8, taken on the line 10—10 of Figs. 2 and 3 and with the parts 25 in the position corresponding to a cylinder dumping operation; and

Fig. 11 is an electrical diagram of the operating and control circuits.

On longitudinally extending main frame members 15 and 16 are rigidly mounted end heads 17 and 17a which support the casing 18. The upper portion of the casing is provided with a slidable door 19 having a supply trough 20 and a handle 21. The door is slidable in guides 22 and 22a. 30
Because a washing machine of the dumping type must have a door uninterrupted throughout the length of the machine, means is provided for supporting the door so that it is easily moved. The means shown comprises brackets 23 which support studs carrying ball bearing rollers 24 which ride upon the convex surface of the guides 22 and 22a so as to maintain the door 19 in floating position. The upper portions of casing 18 and end frames 17 and 17a together provide a cover segment 25 which is hinged at 26 and opens to permit the lifting of the washing cylinder out of the casing. 35
40

The casing door 19 is partly counterbalanced by spring actuated devices 170 and 170a which are alike and located at opposite ends of the door. As best seen in Figs. 2 and 3, the device 170 comprises a metallic tape 171 fastened to the forward end of door 19 at 172 and extending around and secured to a retrieving pulley 173 which is ro- 45
50
55

tatable about a stationary shaft 174 carried by bracket 175. A coil spring within pulley 173 is fastened at one end 176 to the pulley and at its other end to shaft 174. When the door is closed as shown in Fig. 2 the spring is coiled and thus assists in the opening of the casing door.

Upon the right hand end of the frame members 15 and 16 is supported an end frame construction 27 which is formed of structural members welded together. Upon cross channels of this end frame construction is mounted a base plate 28 supporting the driving motor 29. The motor shaft is connected by a combined flexible drive and brake drum 30 with a shaft 31 which is suitably journalled in a bracket 32 supported on the frame 27. A solenoid operated brake 33 is suitably arranged to coact with the drum 30. Rotatable with shaft 31 is a sprocket 34 which is connected by a drive chain 35 with a sprocket 36 which is rotatable with the main drive shaft 37. This shaft has one end bearing 37a supported by bracket 38, an intermediate bearing 37b supported by a housing 39, and another end bearing 37c which will be presently described.

A two-way clutch connection between shaft 37 and the cylinder rotating mechanism on the one hand and the cylinder lifting or dumping mechanism on the other hand provides means by which the operator may select the various operations of the machine as desired. This construction is best seen in Fig. 5 where the right half of the clutch mechanism will be described, it being understood that the left half of the clutch mechanism is exactly the same, similar parts being given similar reference characters with the suffix *a*. Sleeve 40 is keyed to shaft 37 and a plurality of clutch disks 41 are keyed to the sleeve. An adjusting collar 42 controls the clearance between the coacting clutch disks. A cage 43 rigidly connected with the sprocket 44 on the one hand or with the brake drum 45 on the other is drivingly connected with a plurality of clutch disk members 46. This connection as shown in Figs. 8 and 10 permits longitudinal movement of disk members 46 relative to the cage 43 during the engagement and release of the clutch. Springs 47 normally bias the clutch disks 46 away from the clutch disks 41. A plurality of pawls 48 pivotally supported by the sleeve 40 have upwardly extending arms 49 adapted to press the disks 46 toward the collar 42 when the horizontally extending arms 50 are engaged by slidable keys 51 whose ends are bevelled in a manner to engage the ends 50 of the pawls and rotate them clockwise as shown in connection with pawls 48a or counterclockwise in connection with pawls 48 as will be readily understood. The keys 51 are slidable by mechanism presently to be described. For controlling the adjustment of collar 42 an adjusting pin 52 engages in suitable openings 53 in plate 54. The pin 52 is spring pressed toward the plate and may be held out of engagement with the coacting holes by a handle 55 while the collar 42 is turned.

The mechanism for shifting the clutch controlling keys 51 is as follows: The keys are rigidly mounted in a clutch ring 56 which is engaged by a yoke 57 which in turn is secured to shaft 58. This shaft is journalled in brackets 59 and 60 and carries at its right hand end an arm 61 which is connected by link 62 with an arm 63a which is rigid with the operating lever 63 pivotally mounted at 64 in a suitable bracket 65. The bracket 65 carries notches engageable

by a detent 66 spring pressed upwardly in the lever 63 and controlled by a button 67. By manipulation of the button 67 the lever 63 may be placed in neutral position as shown in full lines in Fig. 2 wherein neither of the clutch mechanisms is engaged or in the forward position shown in full lines in Fig. 8 corresponding to engagement of the left hand clutch member of Fig. 5 for rotating the cylinder or, with the lever toward the rear as shown in full lines in Fig. 10, the right half of the clutch mechanism of Fig. 5 is engaged for a cylinder lifting or dumping operation.

With the left half or forward clutch engaged as shown in Fig. 5, shaft 37 rotates drum 45 which in turn supports the bearing 37c for shaft 37. A solenoid operated brake 68 is adapted to coact with the drum 45. Drum 45 is keyed to shaft 69 which is suitably journalled in housing 70. Rigid with shaft 69 is a bevelled pinion 71 which meshes with a bevelled pinion 72 rigid with shaft 73. This shaft is suitably journalled at the other end in bracket 74. Keyed to shaft 73 is a pinion 75 which meshes with a ring gear 76 which in turn is keyed to a gudgeon 77 which is connected with the washing cylinder 78 within the casing 18. It will be understood that this washing cylinder is of the usual perforated type having a circumferentially slidable door at one point about its periphery. The gudgeon 77 (and a similar gudgeon is provided at the opposite end of the cylinder) is journalled in a lifting arm 78 which by a suitable bearing at 79 is mounted to rotate freely about shaft 73. It is not essential to my invention that one shaft 35 be utilized for mounting pinion 75 and for providing the bearing 79 but one of the advantages of my invention lies in the coaxial mounting of the pinion 75 and the pivots for the lifting arms 78 and 78a. The bearing 79a for lifting arm 78a at the other end of the cylinder is therefore axially aligned with shaft 73.

As mentioned above, the right half of the clutch mechanism shown in Fig. 5 is adapted to drivingly connect shaft 37 with the cylinder lifting or dumping mechanism. When the right half of the clutch is engaged it drives the sprocket 44 which as previously described is rotatably mounted upon shaft 37. This sprocket is connected by drive chain 80 with a sprocket 81 best seen in Fig. 4, which is keyed to shaft 82 which is suitably journalled in the frame 27 and carries a worm 83 which meshes with a worm wheel 84 keyed to shaft 85 which is suitably journalled in brackets 86 and 86a supported on the lower portions of the end frames 17 and 17a. Rotatable with shaft 85 are pinions 87 and 87a which drive the cylinder lifting mechanism at each end of the machine. Since the ends are alike the right end will be described and the similar parts at the left end will be given similar characters with the suffix *a*. Pinion 87 meshes with gear 88 which is rotatable about shaft 89 which is supported by the frame 17. A link 90 is pivotally connected at one end 65 with the gear 88 as shown at 91 in Figs. 7 and 9 and at its other end this link is connected at 92 with the lifting arm 78. Rigid with gear 88 is a cam 93 having a suitable surface as shown in Figs. 6 and 9 to coact with mechanism for lifting the cover segment 25 as the cylinder is lifted out of the casing. To this end a follower 94 adapted to coact with cam 93 is carried by a crosshead 95 which is slidable in suitable guideways 96. The other end of the crosshead is con-

nected by link 97 with the cover segment 25. As gear 88 is rotated the parts move from the position of Fig. 6 to that of Fig. 9 wherein cam 93 has raised the cover segment 25 and link 90 has rotated the lift arm 18 about the bearing 79 on shaft 73 so as to raise the cylinder out of the casting for a dumping operation. Means is provided for moving certain portions of the gear guard covers out of the way during the dumping operation. To this end the portion 98 of the gear guard cover is fastened to the lifting arm 18 and a portion 99 of the gear guard cover is secured to the cover segment 25.

Means is provided for holding the sprocket 44 against drifting movement during operation of the cylinder rotating mechanism. This comprises a detent device best shown in Figs. 8 and 10. Shaft 64 which is movable with the operating lever 63 is journalled at its left end in bracket 100 and adjacent that bracket and keyed to shaft 64 is a bevelled pinion 101 meshing with a bevelled pinion 102 on shaft 103 which in turn is journalled at one end in bracket 100 and at the other end in bracket or housing 39. At its rear end shaft 103 carries an arm 104 which is connected by link 105 with one arm of a bellcrank 106 which is pivotally mounted at 107 on the frame 27. The other arm of the bellcrank has a pin and slot connection 108 with a detent 109 spring pressed upwardly by spring 110. The upper end of detent 109 is adapted to engage between the teeth of sprocket 44 when the parts are in the position of Fig. 8 and prevents drifting of sprocket 44 during the rotation of cylinder 18'. When the operating lever 63 is moved to neutral position as shown in dot-dash lines in Fig. 8 the lost motion of the pin and slot connection 108 is taken up but the detent is still engaged. It is only when the operating lever is moved to the full line position of Fig. 10 that the detent is disengaged from the sprocket 44.

Means is provided for controlling the operating electrical circuits for motor 29 by movement of the control lever 63. To this end shaft 103 has rigid with it an arm 111 which has a pin and slot connection with the operating lever 112 of a master control switch 113. This switch comprises a drum 113a carrying suitable contacts adapted to engage and establish or break operating circuits for the motor as will be presently described.

The electrical control circuits are diagrammatically illustrated in Fig. 11. The main power lines L₁, L₂ and L₃ are adapted to be connected by switches 114 with the motor terminals T₁, T₂ and T₃ respectively, or they are alternatively connected by switches 115 with the terminals T₂, T₁ and T₃ respectively. The motor 29 is so arranged that the changing of the direction of flow by the switches 114 and 115 reverses the direction of rotation of the motor. A reversing control motor 116 is provided which drives a cam shaft operating cams 117 and 118 to make and break contacts 119 and 120 automatically and continuously to cause motor reversal at regular periods during the washing operation.

The contacts of master switch 113 are diagrammatically shown in Fig. 11. The contacts carried by the drum 113a have been marked 121 to 126, while the stationary contacts have been marked A, B, C and D.

Control switches operable according to the position of the casing cover 19 are indicated at 127, 128 and 129. In Fig. 1 these switches are shown mounted upon a suitable bracket 130 in position

to be thrown by cams 127a, 128a and 129a respectively. These three switches are biased toward open position and are only closed when engaged by their respective cams.

Control buttons 131, 132 and 133 are mounted outside the cover at the right hand end of the machine. Button 133 is sufficiently removed from 131 and 132 to require both hands of the operator to press 133 and one of the other buttons simultaneously.

The solenoid for actuating brake 33 is marked 33a on the diagram and the solenoid for actuating brake 68 is marked 68a on the diagram.

With lever 63 in its forward position and the casing door closed, the machine is ready for a washing operation, that is to say the forward clutch portion is engaged as shown in Fig. 5 establishing the train of mechanical connections from motor 29 to the ring gear 76 whereby the cylinder 18' may be rotated and the suitable electrical circuits are connected as follows:

In this position of lever 63, the following contacts are established at master switch 113: 121—A, 122—B, 124—C, and 125—D. Current then flows from L₁ through line 134, contacts A and 121, line 135, contacts 122 and B, line 136, switch 127, line 137 through motor 116, and lines 138 and 139 to L₃. Motor 116 therefore operates continuously so long as this circuit is established and alternately makes and breaks contacts 119 and 120 through rotation of cams 117 and 118. At the same time a circuit is established leading from one of the terminals of switch 127 through line 140, the normally closed set of contacts associated with button 131 in its unoperated position shown in Fig. 11 through lines 141 and 165, the normally closed contacts associated with button 132 in its unoperated position as shown in Fig. 11, line 142, switch 128, line 143 to the contacts 119 or 120 which are alternately opened and closed by the reversing control motor. If contacts 119 are closed the circuit is through line 144, contacts 119, lines 145 and 146, solenoid coil 147, and lines 148, 149 and 139 to L₃. This energizes solenoid core 147a and closes the normally open switches 115 establishing a circuit for rotating motor 29 in one direction. Upon the breaking of contacts 119 and the making of contacts 120 a circuit is completed through those contacts and lines 150 and 151 through solenoid coil 152 and lines 149 and 139 to L₃. Energization of coil 152 actuates the core 152a and closes the normally open switches 114 to establish rotation of motor 29 in the reverse direction.

The motor brake 33 and the cylinder brake 68 are each applied when their respective solenoid coil is deenergized and the brakes are released whenever the solenoid coils are energized. With the washing circuits established as just described the cylinder brake is released so long as the lever 63 is in its forward position establishing the contact at 124—C. The circuit thus established is from line 135 through lines 153 and 154, contacts 124 and C, line 155, coil 68a and lines 156 and 139 to L₃. A circuit is also established from one of the terminals of switch 128 through line 157, coil 33a and lines 158, 156 and 139 to L₃ which energizes coil 33a and releases the motor brake 33.

This rotation of motor 29 alternately in opposite directions continues until either lever 63 is moved to another position or until door 19 is opened. Assuming that door 19 is opened at the end of a washing period, switches 127 and 128 will be opened and switch 129 will be closed. 75

This establishes circuits for "inching" or rotating the cylinder by small increments in either direction to spot the cylinder door opening in registration with the casing door opening for access to the interior of the cylinder or for the arrangement of the cylinder in proper position for a dumping operation.

Assuming the casing door to have been opened at the end of a washing operation, switch 129 is closed as before described and switches 127 and 128 are open. A circuit is thus established through contacts 125 and D, line 159, switch 129, line 160 to the normally open contacts controlled by button 133. If button 133 is closed two alternative circuits are possible through button 131 or button 132 to operate motor 29 in either direction of rotation to move the cylinder by small increments to spot it in the desired position. If button 131 is actuated it closes the lower set of contacts shown in Fig. 11 and establishes a circuit through lines 161 and 162, contacts 131a, lines 163 and 151, coil 152 and lines 149 and 139 to L₃. This causes closing of switch 114 and rotation of motor 29 in one direction so long as buttons 131 and 133 are held actuated. During this period the cylinder brake 68 is held released by the circuit previously described and the motor brake 33 is held released by a circuit through lines 164, 165, the normally closed contacts of button 132 and lines 142 and 157 to coil 33a as previously described.

The alternative circuit through button 132 for rotation of motor 29 in the opposite direction is through contacts 132a, lines 166 and 146, coil 147, and lines 148, 149 and 139 to L₃. During the "inching" operation in this direction the motor brake is released by a circuit established through lines 167, 142, 151 and coil 33a.

For causing a dumping operation lever 63 must be moved to its rearward position as shown in full lines in Fig. 10 which establishes the rear clutch connection shown in Fig. 5 and establishes the following contacts at the master control switch 113 breaking all circuits previously described: Segment 123 engages contact A and segment 126 engages contact D. The casing door 19 must be opened for a dumping operation and a circuit is then established from L₁ through line 134, contacts A and 123, lines 168, 154 and 153, contacts 126 and D, line 159, switch 129 and line 160 to the normally open contacts of button 133. By actuating button 133 and either button 131 or 132, motor 29 may be operated either to lift the cylinder out of the casing or to move it back into the casing depending upon which control button is actuated. To raise the cylinder out of the casing button 131 is depressed establishing a circuit through lines 161 and 162, contacts 131a, lines 163 and 151, coil 152 and lines 149 and 139 to L₃. If button 131 is held depressed long enough it will result in again lowering the cylinder to position inside of the casing due to continuous rotation of gear 88 and cam 93. Generally, however, the control buttons are released when the cylinder reaches the desired dumping position as shown in Fig. 9. During the above described cylinder lifting operation, brake 68 is engaged against drum 45 to prevent movement of the cylinder rotating mechanism. Brake 33 is released by a circuit established through lines 164 and 165, contacts 132, lines 142 and 157 and coil 33a. Upon release of button 131 this circuit through brake 33 is broken, coil 33a is deenergized and the motor brake 33 is applied to hold

the cylinder in the position to which it has been raised.

To lower the cylinder from the position of Fig. 9 to the position of Fig. 6, buttons 133 and 132 are actuated, completing a circuit through line 161, contacts 132a, lines 166 and 146 through coil 147 and lines 148, 149 and 139 to L₃. This rotates motor 29 in the opposite direction and lowers the cylinder into the casing. During this operation a circuit is established through lines 167, 142 and 157 through coil 33a to release the brake 33.

It will thus be apparent that I have provided a master control lever 63 which in one position establishes the necessary mechanical drive connections from motor 29 to cylinder 78' for a cylinder rotating operation while at the same time establishing the proper electrical circuits for the operation of motor 29. With lever 63 in this forward position and with switch 129 open automatic mechanism is operable to alternately drive the motor in opposite directions for a washing operation. Upon the closing of switch 129 manual control circuits are established and the automatic reversing control is disestablished so that the operation of motor 29 in opposite directions is possible for an "inching" or spotting operation. On the other hand a shifting of lever 63 to neutral position breaks all mechanical drive connections and all operating circuits and the movement of lever 63 to the rearward position establishes the mechanical drive connections for a dumping operation and coincidentally establishes the proper electric circuits therefor. Here again a manual control is provided for motor 29 to utilize the reverse circuits therefor to control either the raising or lowering of the cylinder relative to its casing. In all of these operations brakes are automatically engaged and disengaged to permit the free operation of the parts which it is desired to move and coincidentally to prevent movement of those parts which should be held for the safe operation of the machine. I have thus provided both a simple and foolproof control.

While the above description is applicable to a washing machine having any suitable type of washing cylinder closed by a door, an additional operation is possible where the washing cylinder has a plurality of pockets. Such cylinders are in common use, the type most often met with being that wherein the cylinder is divided into three pockets by partition walls extending longitudinally of the cylinder on radial lines. I have indicated the approximate position of such partitions (if this type of cylinder is used) by lines 180 in Fig. 9. It will be understood that such a cylinder construction is similar to that disclosed in Patent No. 1,850,523, granted March 22, 1932, to G. H. West, insofar as the arrangement of partitions and the sliding door for each partition is concerned. In such a machine one of the partitions is shown in dumping position in Fig. 9 and it will be understood that the door of this partition is beyond the outer wall of the casing and opened for a dumping operation. With the parts in the position of Fig. 9, the main control lever 63 may then be moved to its forward position which establishes the driving connection through the forward half of the clutch and establishes the motor control circuits previously described in connection with the "inching" or spotting operation. It is then possible by actuation of button 133 and either button 131 or 132 to rotate the cylinder 78' in either direction to 75

spot one of the other compartments in dumping position. During this operation brakes 68 and 33 are released each time the control buttons are actuated but are immediately applied when the buttons are released and so hold the cylinder in any position to which it is rotated.

What I claim is:

1. In a washing machine, a casing, a rotatable washing cylinder therein, means for rotating said cylinder, means for shifting said cylinder bodily relative to said casing, a power member, a two-way clutch having operative connections with said power member and with each of said means, said clutch having positions and being arranged for alternatively placing each of said means in operative relation with said power member while simultaneously disconnecting the other of said means from operative connection with said power means, said clutch having a neutral point between said positions, a control member for moving said clutch to said operative positions, and means actuated by said control member for positively stopping all operative parts when said clutch is at said neutral point.

2. In a washing machine, a casing, a rotatable washing cylinder therein, means for rotating said cylinder, means for shifting said cylinder bodily relative to said casing, a power member, a control member having two operative positions and a neutral point between said positions, and means actuated by said control member in each of its two positions for operatively connecting said power member with one of said means while disconnecting said power member and the other of said means, and means actuated by said control member for positively stopping all operative parts when said control member is at said neutral point.

3. In a washing machine, a casing, a rotatable cylinder therein, said cylinder being arranged for a dumping movement out of and into said casing, an electric motor, selectively operable connections between said motor and said cylinder, one for rotating said cylinder and another for causing said dumping movement, two electrical circuits for operating said motor in opposite directions, each of said circuits including manual control means operable at will to select the direction of rotation desired, and one control member having positions for establishing either the connection for said cylinder-rotating operation or the connection for said cylinder-dumping operation, said control member in each of its positions being arranged to connect each of said circuits with said motor.

4. In a washing machine, a casing, a rotatable cylinder therein, said cylinder being arranged for a dumping movement out of and into said casing, an electric motor, selectively operable connections between said motor and said cylinder, one for rotating said cylinder and another for causing said dumping movement, two electrical circuits for operating said motor in opposite directions, automatic means for continuously and alternately connecting said circuits with said motor, manual means for selectively connecting each of said circuits with said motor, and a single control member having operative connections for coincidentally establishing said cylinder rotating connection and for starting operation of said automatic means in one position, and in another position establishing said cylinder dumping connection and selecting said manual means.

5. In apparatus of the class described, a casing, a rotatable cylinder therein, said cylinder being

mounted for a lifting movement out of and into said casing, a single control member having operative connections in one position for causing said rotational movement and having operative connections in another position for causing said lifting movement, and manually operated means for controlling the direction of each of said movements at the will of the operator.

6. In apparatus of the class described, a casing, a cylinder mounted therein for rotational movement, said cylinder being mounted for a lifting movement out of and into said casing, means for causing each of said movements including a single control member having positions for causing each of said movements, and manual means common to both movement-causing-means for controlling the direction of each of said movements.

7. In a washing machine, a casing, a rotatable washing cylinder therein, an electric motor, an operative connection between said motor and cylinder for shifting said cylinder bodily relative to said casing, a normally applied brake for holding said connection in any of its operated positions, an electrically operated device for releasing said brake, a second operative connection between said motor and said cylinder for causing rotation of said cylinder, a normally applied brake effective upon said second connection for holding said cylinder against rotation, an electrically operated device for releasing said last named brake, and means for simultaneously energizing said motor and one of said devices, whereby each of said brakes is normally applied and released only when said motor is energized.

8. In a washing machine, a casing, a rotatable washing cylinder therein, an electric motor, an operative connection between said motor and said cylinder for shifting said cylinder bodily relative to said casing, a normally applied brake operative on said connection for holding said cylinder in any position to which it is shifted, an electrically operated device for releasing said brake, and one circuit for energizing said motor and said device, whereby said brake is released during a cylinder shifting operation and applied when said operation ceases.

9. In a washing machine, a casing, a rotatable washing cylinder therein, means for rotating said cylinder, means for shifting said cylinder bodily relative to said casing, an electric motor, a two-way clutch having operative connections with said motor and with each of said means, said clutch having positions on opposite sides of a neutral point and being arranged in each of its positions for placing one of said means in operative relation with said motor while simultaneously disconnecting the other of said means from operative connection with said motor, normally applied brakes, one effective on each of said means for holding it against operation, electrically operated devices, one for each brake adapted when energized to release its associated brake, means for supplying electric current to each of said devices by movement of said clutch to position for operating its associated means, and means for deenergizing said devices by movement of said clutch to its neutral point, whereby both brakes are applied when said clutch is in neutral position.

10. In a washing machine, a casing, a rotatable washing cylinder therein, means for rotating said cylinder, means for shifting said cylinder bodily relative to said casing, a power means, a control member having operative positions on opposite sides of a neutral point adapted respec-

tively to cause an operative connection between said power means and one of said first or second named means, means for locking said cylinder shifting means against operation, and said control member having an operative connection with 5 said locking means for holding it in locking position when said control member is in cylinder rotating causing position or in neutral position.

11. In a washing machine, a casing, a reversibly rotatable cylinder therein, said cylinder being 10 mounted for shifting movement out of and into

said casing for a dumping operation, an electric motor, selectively operable connections between said motor and cylinder for causing said rotational and shifting movements respectively, control means for establishing each of said connections at will, circuits for operating said motor in opposite directions to cause said movements, and manual means common to said circuits for controlling the direction of motor operation. 5
